CLAIM

The ornamental design for a bracket, as shown and described.

DESCRIPTION

FIG. 1 is a perspective view of a first embodiment of a bracket showing my new design;

FIG. 2 is a front elevational view thereof;

FIG. 3 is a left side elevational view thereof, with the right side elevational view being a mirror image thereof;

FIG. 4 is a perspective view of a second embodiment of a bracket showing my new design;

FIG. 5 is a front elevational view thereof;

FIG. 6 is a top plan view thereof; and,

FIG. 7 is a left side elevational view thereof, with the right side elevational view being a mirror image thereof.

The parts illustrated in broken lines in FIG. 3 and 7 form no part of the claimed design.
